GREETING CARD

Theodore Markoff, Providence, R. I., assignor to
The Paramount Line, Inc., a corporation of
Rhode Island

Application November 29, 1937, Serial No. 177,011

1 Claim. (Cl. 40—159)

My present invention relates to greeting cards, such as Christmas and birthday cards, and has particular reference to a novel ornamentation therefor.

5 The principal object of my invention is to provide an ornamental attachment for a greeting card or the like, which will enhance the attractiveness and value of the card to the recipient.

10 It is a further object of my invention to provide a device for rendering a greeting card more personal.

15 Another object of my invention is to provide a simple attachment for a greeting card which may be removed from the greeting card and may be separately used as a personal reminder.

20 An additional object of my invention is to provide an attachment for a card which is adapted to receive a photograph such as a personal portrait, the parts being so arranged as to produce a three dimensional lifelike erect.

25 With the above and other objects and advantageous features in view, my invention consists of a novel arrangement of parts more fully disclosed in the detailed description following, and more specifically defined in the claim appended thereto.

In the drawing:

30 Fig. 1 is a perspective view of a greeting card comprising the novel invention;

35 Fig. 2 is a detail showing the appearance of the attachment as purchased, ready to receive an inserted photograph;

40 Fig. 3 is an enlarged central horizontal section through the attachment and the associated greeting card parts;

45 Fig. 4 is a perspective view showing the back of the portrait frame;

50 Fig. 5 is a perspective view of the magnifying lens.

55 It has been found desirable to provide a greeting card with an attached frame in which a photograph such as a portrait of the sender may be inserted, the frame including a magnifying lens which is positioned directly over the portrait so as to add depth to the picture and thus render the portrait more lifelike. The parts are preferably so arranged that the portrait holding attachment may be removed from the greeting card and may have inserted therein a replacement back of any desired form, so that it may be preserved independently of the greeting card if desired. To this end I have provided a simple arrangement of parts which may be readily de-

tached from the greeting card, as hereinafter described.

In the drawing, the greeting card 10, which may be of any desired shape and may have any desired ornamentation and greetings thereon, 5 has a portrait holder 11 mounted thereon at any place desired, this portrait holder consisting of a portrait frame 12, see Fig. 4, which as shown is preferably stamped from sheet metal and is generally box-like in form and open at the back, 10 the sides and bottom 13 forming an enclosure when mounted on the greeting card, and the top being open to permit insertion of a portrait, as hereinafter described.

An opening 14 of any desired shape, but preferably of circular form, is formed in the frame 12, and the sides 13 of the frame are provided with a plurality of prongs 15 in order to lock the frame securely to the greeting card. Before locking the frame to the greeting card, a magnifying lens 16 is preferably positioned so as to extend outwardly from the opening 14, the lens 16 being of greater diameter than the opening so that the locking of the frame to the greeting card will securely lock the lens against removal, 20 while at the same time leaving a thin space directly in back of the lens for receiving the portrait. The prongs 15 securely clamp the frame to the greeting card; additional prongs such as 15a being utilized if desired, to positively lock the 30 lens in place. As shown in Fig. 3, the prongs are pushed through the card 10 and then bent over to effectively lock the frame to the card.

The greeting card thus contains ornamentation and printed or engraved greetings, and in 35 addition contains a picture frame in which a personal portrait may be inserted, the use of the magnifying lens producing an illusion of depth and simulating a lifelike effect. After the greeting card has been received, it may be kept with 40 the picture frame mounted thereon, or the picture frame may be removed from the greeting card and a replacement back inserted, the prongs 15 being opened to first permit removal from the greeting card and then bent to lock the back in 45 place. The frame may be provided with a conventional back and an easel so that it can be set up on a table, bureau or the like.

The preferred frame is made of metal, for ready attachment to the greeting card; but the 50 frame may be formed of the material of the card itself, as by stamping of the like, the magnifying lens being mounted in place so as to permit the insertion of a photograph in back thereof. 55

While I have described a specific constructional embodiment of my invention, it is obvious that changes in the materials used, and in the shape and relative arrangement of the parts, may be made to suit the requirements for different mountings, without departing from the spirit and the scope of the invention as defined in the appended claim.

I claim:

10 A greeting card comprising an ornamental

card having a portrait frame fixed thereto, said frame having sides, a bottom, and an open top, said frame having an opening, a magnifying lens in said opening, said lens being spaced from said card to permit insertion of a photograph adjacent the lens, and a plurality of prongs integral with the sides and bottom of said frame for locking said frame to said card.

5 THEODORE MARKOFF. 10
